Inventor

Henry G. Leach

By his Attorney

Dest K. Schmid

UNITED STATES PATENT OFFICE.

HENRY G. LEACH, OF BROOKLYN, NEW YORK.

TELEPHONE RECEIVER.

Application filed November 29, 1921. Serial No. 518,455.

To all whom it may concern:

Be it known that I, HENRY G. LEACH, a citizen of the United States, and a resident of Brooklyn, in the county of Kings and State of New York, have invented certain new and useful Improvements in Telephone Receivers, of which the following is a specification.

The invention relates to improvements in telephone receivers, more particularly such as are employed for the reception of radio signals; and it has for its object to render receivers of this type highly sensitive.

The nature of the invention, however, will best be understood when described in connection with the accompanying drawings, in which—

Fig. 1 is a vertical section thru the improved receiver.

Figs. 2 and 3 are transverse sections thereof taken on the lines 2—2 and 3—3 respectively, and looking in the direction of the arrows.

Similar characters of reference designate corresponding parts thruout the several views.

Referring to the drawings, 10 designates a suitable casing in the bottom of which is mounted a permanent magnet 11 having a pair of outwardly directed pole shoes 12, which magnet and shoes are respectively of steel and iron and laminated, as shown. The pole pieces 12 are surrounded by windings 13 and cooperate with a diaphragm 14 held to the casing by a cap 15, all of which is well understood and forms no part of the present invention.

In accordance with the invention, there is provided over the inner faces of the respective pole shoes a copper strip 16 and a copper strip 17; and the same may be brought around the under faces of the shoes to the magnet. There is provided, also, to encircle the respective windings 13 a copper

sheath 18 and a copper sheath 19, split vertically to prevent the formation of eddy currents. The top of each windings may, furthermore, be covered by a suitable disk of insulation or metal 20.

The distributed capacity of the one coil with respect to the other is thereby altered through the interposition of the sheaths. It is well known that detrimental effects result from unequal distributed capacity in a coil through which currents resulting in high audio frequencies are flowing; and by thus providing an equalizing capacity, an even distribution of potential is maintained between two coils and better reception of high (from 1000 to 2000) audio frequency vibrations is obtained. A particularly sensitive instrument is thus provided which will be responsive to extremely weak currents and affords a most satisfactory receiver, especially for such purposes as the reception of radio signals.

I claim:

1. In a telephone receiver: a magnet having two pole shoes, and a copper sheath along each of the inner faces thereof.
2. In a telephone receiver: a magnet having two pole shoes, a winding about each shoe, and a copper sheath about each of the windings.
3. In a telephone receiver: a magnet having two pole shoes, a copper sheath along the inner face of each pole shoe, and a copper sheath about each winding.
4. In a telephone receiver: a magnet having two pole shoes, a copper sheath along the inner face of each pole shoe, a winding about each pole shoe, and a copper sheath about each winding and split longitudinally.

Signed at New York, in the county of New York and State of New York, this 26th day of November, A. D. 1921.

HENRY G. LEACH.
